AUTOMATIC AND SEMIAUTOMATIC TELEPHONE EXCHANGE SYSTEM

Gerald Deakin, New York, N. Y., assignor to International Standard Electric Corporation, New York, N. Y., a corporation of Delaware

Application February 12, 1944, Serial No. 522,064

5 Claims. (Cl. 179—27)

This invention relates to new and useful improvements in class of service identifying arrangements for telephone systems.

The object of the invention is promptly to identify the class of service to which the calling line is entitled without interfering with other customary operations, such as calling line identification and metering.

With this object in view, the service to which a line is entitled is indicated by a characteristic potential, e. g. a negative D. C. potential, of certain voltage, applied to a contact, e. g. a test contact individual to the line. By means, such as identification finders, electronic discharge devices may be connected with the contact. The discharge devices will variably respond, depending on the potential existing on the contact, and will thus convey the required information.

The drawing is a diagrammatic illustration of as much of a telephone exchange system as is necessary for a clear understanding of the invention. For further details of the system, reference should be had to my co-pending applications, Serial No. 484,184, filed April 23, 1943, and Serial No. 491,628, filed June 21, 1943, and the applications and patents mentioned therein.

It is assumed that in the absence of a special identification signal, the register will operate in the normal way to control the establishment of a connection, as described in said co-pending applications.

The class of service to which the calling line is entitled, is indicated by a distinguishing potential $-S$, which is applied over a relatively high (e. g. 10,000 ohms) resistance rs to the t or test wire of a subscriber's line under the control of the customary cut-off relay COR of the line. The test wire is, of course, multipled to the terminal banks of line finders and final selector switches. This potential will remain on the t wire during conversation. However, on account of the high resistance of rs , the line may be identified by applying to the t wire a positive potential, in the manner disclosed in my co-pending applications. Such a positive identification potential is placed momentarily on the t wire through a relatively low resistance, thereby destroying the effect of the permanently connected service identification potential $-S$.

The $-S$ potentials may be -26 to -64 volts, the different classes of service being distinguished by a spacing of 2 volts from an adjacent class. The calling line number identification potentials are also spaced from one another by 2 volts and, since they are positive, they may include some

of the voltages used for class of service identification.

In addition to the above characteristic potentials, each line has a characteristic $-N$ and $-C$ potential applied to its t wire over a back or a front contact of the line relay LR and a back contact of COR. Depending on the units digit of the line, the $-N$ potential may be from -2 to -20 volts. The $-C$ potential may be -22 volts and, when applied to the t wire, indicates that the line is calling.

When a call is initiated, the first finder connects with the line and causes the energization of COR over the control wire c . COR will connect the t wire from the armature of line relay L_r and connect it with the $-S$ source of potential over resistance rs . The call is extended from the first finder to a B link where a metering relay MR is connected with the t wire over a gas valve GV. An identification relay GSR, common to a group of lines, is connected over a resistance r and a positively poled rectifier S with the t wire in the line finder or link circuit associated with the first line finder. The gas valve GV breaks down to permit the operation of the metering relay MR only when negative potential of 80 volts is applied to the t wire. This is the booster metering potential. Thus, the normally connected relatively low $-S$ potential will not cause energization of the metering relay.

As described in my co-pending application, Serial No. 491,628, the register or a toll operator's position is provided with a string of triode circuits for the purpose of identifying the number of the calling line. In the present case, these circuits are used for scanning the service classification, there being as many pairs of triodes and associated gas valves as there are service classes to be identified.

When a common lead X leading to the valve circuits, is connected under the control of the register or an operator's key over first and second identification finders, first line finder and second line finder, with the t wire of the calling line, one pair of class identification triodes V_1 , V_2 ; V_3 , V_4 etc., will operate. As explained in my co-pending application, Serial No. 491,628, only that pair of triodes operates to the grids of which the same potentials are connected. In the present case, V_1 and V_2 will operate (V_4 having $-S_2$ potential applied to its grid), cause the momentary lighting of the associated gas valve GV and the energization of GVR and GSR.

The class of service to which the calling line is entitled is thus identified and may then be re-

corded or indicated in any well-known manner. No -S potential is placed on the *t* wires of unrestricted main lines and therefore the register or the operator would not receive the special signal that other lines would give.

What is claimed is:

1. In a telephone exchange system, a plurality of subscribers' lines each comprising a pair of talking conductors and a test conductor, a central exchange, means for extending said lines to said exchange, a source of D. C. potentials from which are derived potentials characteristic of different classes of service, means for applying to the test conductors of calling lines a D. C. potential characteristic of the class of service to which said lines are entitled, an electronic discharge device at said exchange for each class of service, a relay associated with each discharge device and arranged to operate only when two D. C. potentials applied to respective electrodes of said device bear a predetermined relationship, means at said exchange for connecting to an electrode of each of said devices a different D. C. potential characteristic of each class of service and means for extending the test conductor of a calling line in multiple to another electrode of each of said devices.

2. In a telephone exchange system, subscribers' line circuits, means including automatic switches for connecting a calling line to a called line, one of said switches having terminals for a group of lines, a source of D. C. potentials from which are derived characteristic class of service potentials, means for applying to terminals of calling lines the class of service D. C. potential to which they are entitled, an electronic discharge device for each class of service, means for applying a different characteristic D. C. potential identifying the different classes of service to the different devices, switching means for connecting said devices with a terminal of the calling line, and means connected with each discharge device so arranged that it operates only when the potentials applied to the associated devices bear a predetermined relationship to one another.

3. In a telephone exchange system, subscribers' line circuits, means including automatic switches for connecting a calling line to a called line, one of said switches having terminals for a group of lines, a source of D. C. potentials from which are derived characteristic class of service potentials, means for applying to terminals of calling lines the class of service potential to which they are entitled, a plurality of pairs of multi-electrode discharge devices, a different characteristic potential identifying the different classes of service being applied to the grid of the first device in each pair, switching means for connecting the grids of all the second devices with the terminal of the calling line to which the class of service

potential is applied, and means connected with each pair of discharge devices and so arranged that it operates only when the potentials applied to the grids of both devices associated therewith bear a predetermined relationship to one another.

4. In a telephone exchange system, subscribers' line circuits, means including automatic switches for connecting a calling line to a called line, one of said switches having talking and test terminals for a group of lines, a source of D. C. potentials from which are derived a characteristic class of service potential and a characteristic number identifying potential assigned to each line, and a certain potential designating the calling condition of a line, means for applying all said potentials to the test terminal of the line, the calling potential upon the initiation of a call on a line, the number identifying potential while the line is idle and the class of service potential when the calling line has been connected, a plurality of pairs of triodes, a different characteristic potential identifying the different classes of service being applied to the grid of the first triode in each pair, switching means for connecting the grids of the second triodes with the test terminal of the calling line, and means connected with each pair of triodes so arranged that it operates only when the potentials applied to the grids of both tubes associated therewith bear a predetermined relationship to one another.

5. In a telephone exchange system, subscribers' line circuits, means including automatic switches for connecting a calling line to a called line, one of said switches having talking and test terminals for a group of lines, a line and a cut-off relay for each line, a source of D. C. potentials from which are derived a characteristic class of service potential and a characteristic number identifying potential assigned to each line, and a certain potential designating the calling condition of a line, all said potentials being applied to the test terminal of the line, the calling potential over a front contact of the line relay and a back contact of the cut-off relay, the number identifying potential over back contacts of the line and cut-off relays and the class of service potential over a front contact of the cut-off relay, a plurality of pairs of triodes, one pair for each class of service, a different characteristic potential identifying the different classes of service being applied to the grid of the first triode in each pair, switching means for connecting the grids of all the second triodes in parallel with the test terminal of the calling line, and a gas valve connected with each pair of triodes over a circuit so arranged that the gas valve operates only when the same potentials are applied to the grids of both tubes associated therewith.
